UNITED STATES PATENT OFFICE.

DAVID R. BONE, OF OGLESBY, TEXAS.

HEAT-PRODUCING PROCESS.

1,281,902.

Specification of Letters Patent. Patented Oct. 15, 1918.

Application filed June 26, 1917. Serial No. 177,068.

To all whom it may concern:

Be it known that I, DAVID R. BONE, a citizen of the United States of America, residing at Oglesby, in the county of Coryell and State of Texas, have invented certain new and useful Improvements in Heat-Producing Processes, of which the following is a specification.

My invention relates to a process of producing heat and conserving heat for use in kilns, furnaces for burning lime, furnaces for boilers, furnaces for manufacturing enterprises, and for similar purposes; and the object is to provide a process of increasing the number of heat units from fuel and for conserving the heat when produced, to provide a process of burning fuel without wasting the heat units, to provide a process of burning fuel whereby the cheaper as well as the better grades of fuel will produce more heat in proportion to the amount of fuel burned; and to provide a process of burning fuel wherein cold air is excluded from the burning of the fuel. The patent issued to me on June 12, 1917, No. 1,229,706, shows how such process is carried out in practice. Other objects and advantages will be fully explained in the following description and the invention will be more particularly pointed out in the claims.

Reference is had to the accompanying drawings which form a part of this application.

Figure 1 is a vertical section of a furnace and apparatus for burning fuel and preheating the air, showing a kiln in conventional form connected to the furnace. Fig. 2 is an enlarged sectional view of a stoker. Fig. 3 is a longitudinal section of the revolving feeder.

Similar characters of reference are used to indicate the same parts throughout the several views.

The results of the process herein described are obtained by feeding the fuel to the combustion chamber in a powdered form and by letting only preheated air into the combustion chamber and by excluding cold or unheated air from the combustion chamber. Generally, the heat is produced in a different

chamber from the chamber in which the heat is to be utilized. In the drawings, a kiln 1 is shown in conventional form provided with a flue 3. A furnace 4 is provided with grate bars 5, a door 6, and stokers 7. Instead of placing an ash-box under the grate bars 5, as usual, a chute 8 is provided with a flared upper end or mouth 9 to receive the ashes and hot embers which fall through the grate bars 5. The ashes fall down the inclined chute to a box 10 from which they can be removed through a door 11. Provision is made for a fire within the box 10. Grate bars 12 are provided for receiving the fuel and supporting the same for combustion. The object of the fire in the box 10 is to heat all air that is fed to the furnace 4. The air is heated not only by the fire which is maintained in the box 10, but is also heated by the embers which fall through the grate bars 5. The box 10 is provided with a door 13, which may be used for supplying fuel to the fire on the grate bars 12 and for admission of air which is to be heated. The heated air will rise up through the fuel 14 which is being consumed in the furnace 4. The fuel for furnace 4 is preferably fed in powdered form by means of stokers 7. The fuel will fall into the fire zone 15 where the particles of fuel will be oxidized and largely converted into gas. The heat and burning gases pass directly into the kiln 1. A plurality of stokers 7 may be provided and each stoker consists of a casing 16 with openings 17 into a hopper 18 which contains fuel and corresponding openings 19 for dropping the fuel into the fire zone 15 within furnace 4. The fuel is fed by a revolving feeder 20. The feeder 20 may be revolved by any suitable means. In operation, a cavity 21 formed in the feeder will be turned to an opening 17 in the casing 16 and instantly a charge of fuel will fill the cavity 21 in the feeder and on continuous revolving of the feeder, the charge of fuel will be dumped into the furnace 4 through the opening 19 in the casing 16, and on each revolution of the feeder 20, each cavity 21 will gather a charge of fuel and dump the same into the furnace 4.

In order to prevent air from entering the fur- 100

nace 4, short pipes 23 may be connected with casing openings 19 and project down into the furnace 4.

5 A valve or damper 24 is provided for regulating the flow of heated air through the chute 8. A valve or damper 25 is also provided for regulating the passage of heat and burning gases from the furnace 4 into the kiln 1.

10 The fire on the grate bars 12 may be a slow burning fire to heat the incoming air which will rise through the chute into the main furnace 4. The air in going up the chute will be further heated by the falling embers 15 from the grate bars 5. The air will thus be preheated before it comes in contact with the fuel in the furnace 4 where the principal combustion takes place. The cold air or air in the normal condition is thus excluded and 20 only preheated air is let into the furnace or combustion chamber. The burning of the fuel will create the necessary draft to force the heat and burning gases into the kiln 1. The air is subjected to a process of preheating and after the air is thus treated, only 25 such quantity of air as is necessary and no more than is needed is allowed to enter the combustion chamber for oxidizing the contents of the chamber. The excluding of the 30 cold air from the furnace or combustion chamber is important because the combustion will not be impeded or hindered by the cold air which would absorb heat units. The heat produced is thus conserved, as the heat 35 will not be consumed in heating cold air. The gases created by the burning fuel are protected from being impaired for heating purposes because they are not exposed to air which has not been preheated. A success- 40 ful process has been developed for securing a complete combustion of all the gases as they are being produced, thus conserving and preventing any waste of heat units. The process is smokeless because all the fuel par- 45 ticles will be consumed. The combustion chamber may be connected with a kiln, as shown, or the heat created in the combustion chamber can be forced into any other furnace or place for use for manufacturing or other 50 purposes.

The degree of heat in the furnace can be regulated by the stoking devices which can be set to feed more or less fuel to the combustion chamber and by regulating the 55 amount of preheated air which is furnished to the combustion chamber. The amount of preheated air which comes through the chute 8 can be regulated by the damper 24. The invention is particularly a pulverized fuel 60 combustion process so that all the fuel can be consumed. At the same time oxygen only in sufficient quantities is furnished to combine with all the carbon elements. The process is dependent on a specially arranged

furnace, as shown in the drawings, having a 65 combustion chamber dependent upon a supply of fuel being fed thereto in powdered form through specially devised apparatus connected therewith, and also on the provision for preheating air to be furnished thereto and for preventing all cold draft from entering the combustion chamber during combustion. Lignite coal especially and the cheaper fuels are dependent on this process to be utilized as a fuel efficiently enough 75 for all purposes. The door 6 is not a fuel supply opening generally,—not to be used except for starting a fire on the grate bars 5 to begin the operation. The door 6 is then closed up air-tight and the fuel in powdered 80 form is supplied through the holes 23, as shown in the top of the furnace. No air passes in with the fuel supply and preheated air necessary for oxidizing is admitted by way of the chute 8.

85 What I claim, is,—

1. The herein described process of producing and conserving heat which consists in starting a fire in a chamber and then closing the chamber, feeding fuel by gravity into 90 the chamber in powdered form and at the same time excluding cold air from said chamber, and supplying preheated air to said chamber.

2. The herein described process of producing heat which consists in maintaining a fire in a closed chamber and at the same time excluding cold air from said chamber, supplying preheated air to said chamber, and feeding fuel by gravity to said chamber 100 in powdered form.

3. The herein described process of producing and utilizing heat which consists in maintaining a fire in a closed combustion chamber and at the same time excluding cold air therefrom and supplying preheated air to said chamber as required, feeding fuel by gravity in powdered form to said fire, and transmitting the heat so produced to a place 105 for use.

4. The herein described process of producing and utilizing heat which consists in maintaining a fire in a chamber closed, against the admission of cold or normal air, preheating air and supplying the same directly to said closed chamber, supplying fuel to said chamber by gravity and at the same time excluding cold air therefrom, and transmitting the heat so produced to a place of 115 use.

5. The herein described process of producing and utilizing heat which consists in burning fuel in a closed combustion chamber, preheating air in a chamber in communication with said combustion chamber 125 for supplying heated air thereto for maintaining combustion therein, feeding fuel in powdered form by gravity to said chamber

and excluding cold air therefrom, and transmitting heat so produced to a place of use.

6. The herein described process of producing and utilizing heat which consists in burning fuel in a closed combustion chamber from which cold or normal air is excluded, supplying fuel to said chamber by gravity in powdered form in regulated quantities

without admitting cold or normal air therewith, preheating air and admitting the same 10 to said combustion chamber and transmitting heat so produced to a place of use.

In testimony whereof, I set my hand, this 23rd day of June, 1917.

DAVID R. BONE.
